UNITED STATES PATENT OFFICE.

AUTHUR B. CAREY, OF HUTCHINSON, KANSAS.

CARTON.

1,079,394.

Specification of Letters Patent.

Patented Nov. 25, 1913.

Application filed May 2, 1911. Serial No. 624,629.

To all whom it may concern:

Be it known that I, ARTHUR B. CAREY, a citizen of the United States, residing at Hutchinson, in the county of Reno and State 5 of Kansas, have invented new and useful Improvements in Cartons, of which the following is a specification.

This invention relates to improvements in cartons or collapsible boxes and packages, 10 and more particularly to that class of cartons, boxes and receptacles which are constructed of card, card-board, and the like, and are used to contain salt, pepper, flour, washing compounds and many other such 15 substances which are used for domestic and other purposes.

The object of the invention is to provide a collapsible box, package or receptacle which will be arranged to permit salt, and 20 similar substances, to be poured out in a relatively small and convenient stream.

Another object of this invention is to provide means in such a box or carton to readily control said stream, or to prevent 25 any salt or the like coming out of the carton, when so desired.

A further object is to provide such a carton, or the like, so arranged that it will be unnecessary to mutilate its parts in any 30 way in order to permit the contents to flow out, and to have such means, and the carton in general so arranged that the improvements therein will not raise the cost of manufacture of the article any appreciable 35 amount although its efficiency and utility be greatly increased.

Having these general objects in view, and others which will appear as the nature of the improvements is better understood, the 40 invention consists substantially in the novel construction, combination and arrangement of parts hereinafter fully described, illustrated in the accompanying drawings, and pointed out in the appended claim.

45 In the drawings Figure 1 is a view in perspective of a collapsible carton embodying the invention. Fig. 2 is a view of the carton shown in Fig. 1 with an end opened out. Fig. 3 is a view showing the tongue 50 of the carton moved to open its orifice, and Figs. 4 and 5 show modifications of the invention.

Similar reference characters refer to similar parts throughout the drawings.

55 Referring in detail to the drawings, 11

represents the sides of an ordinary type of collapsible carton or box, preferably made of card, card-board or the like, and which has its ends formed by bending inwardly the end portions 1, 2, 3 and 4, and the corresponding opposite end portions respectively, of the sides 11, and suitably fastened in position. One of these ends is adapted and arranged to be kept closed in any suitable manner, but the other end has the portion 1, perforated and provided with a hole 10, preferably circular, near the middle of its left-hand edge, while the opposite piece 2 is adapted to be disposed directly on top of the piece 1, and is provided with a relatively large side slot 20, arranged to spread over the hole 10. The end portion 3 is then bent over and placed on top of the piece 2 and is provided with a hole 100, which is arranged to correspond and lie directly over the hole 10 in the end piece 1. The end portion 3 is also provided with a slot 30 for the reception of a tongue 44 which is cut out of the end portion 4, as is clearly shown in the drawings. The end portion 4 is disposed 80 directly on top of the portion 3.

The slots 40, on the side of the tongue 44, provide means for easily removing the tongue from its slot 30, although other convenient means can be used for the same 85 purpose, as for instance, a short loop of string or button fastened to the tongue.

It will be noted that the position of the slot 30, and the length of the tongue is such that on the insertion of the tongue into 90 the slot the holes 10 and 100 are completely closed; on pulling the tongue up a short distance the holes become partially uncovered and the material inside the carton can be poured out, and if it is desired to give a 95 larger stream or flow, the tongue is completely pulled out and the whole area of the hole exposed which permits the flow to increase.

In practice it is customary to paste the 100 portions 1, 2, 3 and 4 together and to allow the tongue to be free to operate in and out of its slot. The pasting of these parts is for obvious reasons.

It would in some cases be advantageous to 105 have either or both ends arranged for the emission of the contents of the carton but for ordinary purposes only one end so treated would be necessary to meet the requirements of the conditions arising.

The advantages of this type of carton or receptacle are many, as for instance, it allows salt, flour, sugar and the like, to be taken therefrom in convenient and controlled quantities; the flow or stream of the contents can be readily and easily started without turning any parts of the carton or mutilating the same in any manner, and when the desired amount of the contents of 5 the carton has been removed the carton can be quickly and securely closed, keeping air and moisture out and providing a highly sanitary closure. As the carton is not mutilated in any manner it can be refilled and 10 used again if so desired. With all of these advantages and beneficial results the cost of manufacturing is practically unchanged as no additional material is required to form this improvement.

20 As I anticipate many modifications of my device I have added, in Figs. 4 and 5, several other forms of my invention, but I do not wish to be limited to these forms or even the number of emission holes or their 25 shape, or in any other way except that necessitated by the prior art, as many modi-

fications of this invention can be made without departing from the principles thereof.

Having thus described the invention, what is claimed as new and desired to be 30 secured by Letters Patent, is:

A collapsible box comprising in combination, a piece of material formed to make a four sided package, said sides having their end portions or flaps adapted to close inwardly and overlap and close the ends of the box, the under portion having a hole therein for the egress of the contents of said package, the second of said flaps having a slot cut out so that the said portion will not 35 obstruct said hole, the third of said portions having a hole therein arranged to be disposed over the hole in the under portion and a slot disposed relatively close to said hole, and an outer portion or flap provided with 40 a tongue adapted to engage with the last mentioned slot and project between the egress holes formed integral therewith.

ARTHUR B. CAREY.
